W. KAISLING

RECEIVER

Filed March 3, 1921

Inventor:
William Kaisling
By Curtis B. Camp,
Attorney

UNITED STATES PATENT OFFICE.

WILLIAM KAISLING, OF CHICAGO, ILLINOIS, ASSIGNOR TO KELLOGG SWITCHBOARD AND SUPPLY COMPANY, OF CHICAGO, ILLINOIS, A CORPORATION OF ILLINOIS.

RECEIVER.

Application filed March 3, 1921. Serial No. 449,396.

To all whom it may concern:

Be it known that I, WILLIAM KAISLING, a citizen of the United States of America, and a resident of Chicago, county of Cook, and 5 State of Illinois, have invented certain new and useful Improvements in Receivers, of which the following is a specification.

My invention relates to receivers and has to do more particularly with the so-called 10 watch-case receivers which are used as head receivers for telephone switchboard operators.

An object of my invention is the provision of a receiver of simplified construction, and 15 in which the weight is reduced to a minimum without impairing the efficiency of the device.

In receivers of the above type as now used, the outer casing of insulating material and the magnets, which are circular in form, are of a size to fit along the inner periphery of the said casing, and these magnets usually make up the greater portion of the receiver weight, and this weight is objectionable because of the strain upon the operator, and by my improved construction 25 the weight is greatly reduced.

A feature of my invention is to provide a receiver of this type with improved binding posts of the concealed type, and the receiver cord terminals are enclosed within 30 the terminal block of the receiver in such a way that they are effectively prevented from being short-circuited.

Another feature of my invention is the provision of a permanent magnet eccentrically disposed with relation to the central opening of the receiver cap, but so constructed as to permit the pole pieces and 40 magnet coils as a whole to be mounted centrally in relation with the diaphragm of the receiver.

Still another feature of my invention is the provision of an improved securing 45 means for fastening the head band to the receiver, whereby it is pivotally supported and held to its supporting means without additional fastening means such as screws.

The above features, as well as others, will 50 be more fully hereinafter described, and for a clearer understanding of my invention reference may be had to the accompanying drawing, in which like reference characters

in the several views denote like parts, and in which—

55

Fig. 1 is a rear view of the receiver of my invention;

60

Fig. 2 is a side view of the receiver;

Fig. 3 is a face view of the receiver of my invention;

Fig. 4 is a face view of the receiver with the ear piece or cap and the diaphragm removed;

65

Fig. 5 is a sectional view of the receiver along the line *a—a* of Fig. 3;

Fig. 6 is a sectional view of the receiver along the line *b—b* of Fig. 3;

70

Fig. 7 is a sectional view along the line *c—c* of Fig. 4 to more clearly illustrate the construction of the binding posts; and

Fig. 8 is a perspective view of the support member to which the head band is secured.

75

Referring now more in detail to my invention as illustrated, it comprises a shallow shell or casing 2 of suitable insulating material, such as moulded bakelite or hard rubber, the said casing 2 being provided with exterior threads 4 at its forward end, upon which is screwed the ear piece or receiver cap 5, which is also of insulating material such as bakelite, the said cap 5 serving to clamp the receiver diaphragm 6 between the forward end of the casing 2 and receiver cap 5. The casing 2 is provided with a rearwardly extending cup member 7 eccentrically disposed in relation with the center of the casing 2, the said cup member 7 being integrally formed with the said casing and the said cup member 7 receiving the permanent magnet M, as will now be described.

80

The permanent magnet M consists of a plurality of horseshoe-shaped pieces 8 of steel or other suitable magnetic material, each of which is permanently magnetized, said magnets being placed one upon another and being of such shape as to rest in the rearwardly extending cup member 7 and fit along the inner periphery of the said cup member 7, with their ends 9 terminating over the portions 10 of the pole pieces 11, as clearly illustrated in Fig. 5. The pole pieces 11 are bent, the portions 10 passing beneath the ends 9 of the permanent magnet M, and the portions 11 extend upwardly in proximity to the receiver diaphragm 6

95

100

105

and carry the magnet coils 12. The permanent magnet M, when resting in the eccentrically disposed cup-shaped member 7, is necessarily eccentrically placed in relation 5 to the center of the casing 2 and the diaphragm 6, but the ends 9 of the magnet M are so positioned in relation with the cup-shaped member 7 as to bring the pole pieces 11 in the center of the diaphragm. The pole 10 pieces 11 and magnet M are secured against movement in the cup-shaped member 7 by means of the screws 13, which pass through suitable openings 15 in the ends 9 of the magnet M and openings 16 in the bottom of 15 the cup-shaped member 7 and have screw-threaded engagement with suitable tapped orifices 17 in the metal rod 18, which rod may be imbedded in a rib on the bottom, outer face of the cup member 7 of the receiver during the moulding operation of the 20 same. The rod 18 also serves as a securing means or supporting means for the receiver head band H, as will be more fully herein-after described.

25 From the above description it may be seen that by providing an eccentrically disposed cup member 7, I am enabled to reduce the size of the magnet considerably, and the magnet M which rests in the eccentrically 30 disposed cup is so constructed as to bring the poles of the magnets in the center with relation to the diaphragm. This type of construction permits the use of a much smaller magnet and reduces the weight considerably, but does not impair the efficiency 35 of the transmitter.

In order to connect the magnet coils 12 in the electrical circuit in which the instrument is to be used, suitable binding posts 40 B are provided. A separate terminal block 20 is provided and is of suitable insulating material such as bakelite, and the terminal studs 21 are provided which are suitably imbedded in the terminal block 20 during 45 the moulding operation of the same. The studs 21 are provided with reduced portions 22, which are threaded and extend through suitable orifices 23 in the bottom of the casing 2 when the said terminal block 20 is in 50 place upon said casing 2. Terminal clips 24 are provided with central orifices of a size to permit them to be slipped over the threaded portions 22 of the studs 21 which protrude through the openings 23 in the casing 2. Lock nuts 26 are provided, which 55 lock nuts have screw-threaded engagement with the threaded portions 22 of the studs 21 and clamp the terminal clips 24 between said nuts 26 and the casing 2. The terminal 60 clips 24 are provided with terminal ends (Fig. 4) to which the terminals of the coils 12 are soldered. When the lock nuts 26 are tightened upon the threaded portions 22 of the studs 21, the said nuts 26 also secure the 65 terminal block 20 to the bottom face of the

casing 2. The portion of the studs 21 which are imbedded in the terminal block 20 are provided with transverse orifices 27, and the terminal block 20 is also provided with openings 28 which are in alignment with 70 said openings 27, and said openings 27 and 28 receive the metal tips 29 of the receiver cord, thus connecting coils 12 with the electrical circuit in which the receiver is to be used, and to secure the metal tips 29 in orifices 27, clamping screws 30 are provided, engaging the centrally tapped orifices 31 in the stud 21. The said screws 30 when tightened clamp the metal tips 29 in the said 75 openings 27 against displacement. The terminal block 20 is provided with an orifice 32 through which the strain cord 33 of the receiver cord is inserted and tied so as to relieve the strain from the cord terminals 29.

80 The receiver head band support comprises a U-shaped member 34 of suitable spring metal upon which the head band H of spring wire is pivotally secured by means of the clip 38 provided with a pair of extensions 39, which are suitably formed over the ends 37 of the wire head band H. The member 38, which supports the head band H, is pivotally secured by means of the pivot-rivet 41 upon the U-shaped member 34 to 85 permit adjustment of the head band H when placed in position upon the head of the operator. To support the U-shaped member 34 to the receiver shell, the rod 18 associated 90 with the casing, as already described, is provided with reduced portions which form pins 42, and the legs of the U-shaped member 34 are provided with orifices 43 of a size to receive the pins 42. The span of the U-shaped member 34 is slightly smaller than 95 the width of the rib 44 formed upon the cup member 7, and to place the member 34 in pivotal engagement with the pins 42 the legs of the U-shaped member 34 are forced 100 apart and released so as to slip orifices 43 over the pins 42. When in this position the legs of the member 34 are under spring tension and hold said member 34 and head band H in pivotal position upon the pins 41 105 and the pivotal support of the head band H by means of the pivot 41 and the pivotal supports of the U-shaped member 34 upon the pins 42 permits a ready adjustment of 110 the receiver so that it can always rest in a correct and easy position against the operator's ear.

115 Having described a specific form of my invention, I do not wish, however, to be limited to the exact structure as illustrated and described, but aim to cover all changes and modifications as will readily suggest themselves in the appended claims.

120 What I claim as new and desire to secure by United States Letters Patent, is:

125 1. In a receiver of the class described,

comprising a diaphragm and a casing provided with an eccentrically disposed cup member intergally formed therewith, a permanent magnet in said cup member, and

5 pole pieces for said permanent magnet positioned adjacent to the center of said diaphragm.

2. In a receiver of the class described, comprising a diaphragm and a casing provided therefor with a rearwardly extending cup member, eccentric to the diaphragm, a permanent magnet in said cup member, pole pieces for said permanent magnet supporting magnet coils and so positioned as to 10 place the said pole pieces at the center of said diaphragm.

3. In a receiver of the class described, comprising a casing provided with a rearwardly extending cup member eccentrically disposed in relation with the center of said casing, said cup member being integrally formed with said casing, a diaphragm, a permanent magnet resting in said cup member eccentrically disposed in relation with the center of said diaphragm, pole piece extensions of said permanent magnet and so positioned as to place the said pole pieces in relation with the center of said diaphragm.

30 4. In a receiver, the combination with an outer casing and a magnet and cooperating parts within said casing, a terminal block, binding posts inserted in said terminal block, screw-threaded extensions for said binding posts extending through openings in the rear wall of said casing, and lock nuts having screw-threaded engagement with the said screw-threaded portions of said binding posts for securing said terminal 35 block to said casing.

5. In a receiver, the combination with an outer casing and a magnet and cooperating parts within said casing, a terminal block, binding posts inserted in said terminal block, screw-threaded extensions for said binding posts extending through openings in the rear wall of said casing, connection means for the magnet coils within said casings between said coils and said binding 45 posts, and lock nuts having screw-threaded engagement with the threaded extensions for securing said terminal block to said casing and securing said connection means in contact relation with said terminals.

55 6. In a receiver, the combination of an outer casing, a magnet and cooperating parts within said casing, a terminal block, binding posts carried by said terminal block, screw-threaded extensions for said binding 60 posts extending through suitable openings in the rear wall of said casing, terminal clips for the magnet coil within said casing, lock nuts having screw-threaded engagement with said threaded extensions for securing said terminal block to said casing and said

terminal clips in contact relation with said terminal, and transverse apertures in said binding posts for receiving the cord tips of a receiver cord.

7. In a receiver, the combination of an outer casing, a magnet and cooperating parts within said casing, a pair of binding posts, a terminal block, said binding posts being concealed within said terminal block, threaded extensions for said binding posts extending from said terminal block and into openings in the rear wall of said casing, lock nuts having screw-threaded engagement with said threaded extension for securing said block to said casing, connection means between said binding posts and the magnet coils in said casing, and each binding post being provided with an aperture for connection to the receiver cord, the terminal block being provided with openings for the receiver cords, and binding screws inserted in each of the said binding posts.

8. In a receiver having an outer casing, a permanent magnet and cooperating parts within said casing, a pair of binding posts, a terminal block, said binding posts being concealed within said terminal block, threaded extensions for said binding posts extending from said terminal block and through openings in the rear wall of said casing, lock nuts in threaded engagement with said threaded extensions for securing said terminal block to said casing, central tapped orifices through said binding posts, transverse orifices in the said binding posts to receive the cord tips of the receiver cord and binding screws having threaded engagement with said central orifices in said binding posts for retaining the cord tips in orifices of said binding posts.

9. In a receiver of the class described, a diaphragm and its electromagnet, a permanent magnet therefor extending angularly to one side of said electromagnet, and an enclosing case provided with an integrally and eccentrically formed pocket of a size to receive said permanent magnet, a cover cap for enclosing said diaphragm, electromagnet and permanent magnet, said diaphragm being clamped between said case and said cover cap.

10. A receiver of the class described, including a diaphragm and its electromagnet, a supporting and enclosing case therefor of insulating material provided with an integrally and eccentrically formed pocket, a permanent magnet for engaging said pocket so that the same is positioned eccentric to said diaphragm, and a cover-cap for said case adapted to engage said diaphragm to secure said diaphragm in operative relation with its electromagnet.

11. In a receiver of the class described, a diaphragm provided with a centrally disposed electromagnet, an enclosing case pro-

vided with an integrally and eccentrically formed pocket, a laminated permanent magnet for engaging said pocket so that said magnet is mounted eccentrically to said diaphragm, and means for securing said permanent magnet in said pocket.

12. In a receiver of the class described, a diaphragm with a centrally disposed electromagnet, an arcuate shaped permanent magnet therefor having a diameter substantially a radius of the diaphragm, an enclosing case having an integrally and eccentrically formed cup member for receiving said electromagnet and said permanent magnet, and means for securing said magnet and said electromagnet in said cup member, said permanent magnet being secured eccentrically to said diaphragm and said electromagnet being secured centrally to said diaphragm.

13. In a receiver of the class described, a diaphragm with a centrally disposed electromagnet and an arcuate shaped permanent magnet therefor, an enclosing case, a cup member integrally formed with an eccentric to said enclosing case for receiving said permanent magnet and said electromagnet so that said magnet is positioned beneath a substantially diametrical section of the diaphragm only and said electromagnet is positioned substantially beneath the center of said diaphragm.

14. In a receiver of the class described, a diaphragm with its electromagnet, an arcuate laminated permanent magnet therefor eccentric to said diaphragm, an angular pole piece for said magnet constituting the core of said electromagnet, and an enclosing case having an integrally and eccentrically formed member for receiving said permanent magnet, electromagnet and said pole piece, so that said magnet is positioned eccentrically to said diaphragm and said electromagnet is positioned centrally to said diaphragm, and means for securing said magnet and electromagnet in position.

15. In a receiver of the class described, a diaphragm and its electromagnet, an enclosing case for them, and a terminal block for the receiver cord terminals, detachably mounted on the exterior of said case, said terminal block adapted to receive the receiver cord terminals and to secure the same to and within said terminal block.

16. In a receiver of the class described, a diaphragm and its electromagnet, an enclosing case for them, a terminal block for a receiver cord terminal on the outside of said case, and mechanical connecting means operated from within the case for attaching and detaching said block, said terminal block adapted to receive the receiver cord terminal and to have the same secured to and within said terminal block.

17. In a receiver of the class described, a diaphragm and its electromagnet, an en-

closing case for them, a terminal block on the outside of the case with means for receiving and holding a receiver cord terminal within said terminal block and a conductor extending into said case and connecting with said electromagnet.

18. In a receiver of the class described, a diaphragm and its electromagnet, a permanent magnet, an enclosing case for them, a terminal block on the outside of said case with a terminal for connection to a receiver cord, the connection of the terminal and receiver cord being within said terminal block, means operated from within said case for attaching said block, said means serving also to connect said terminal and said electromagnet.

19. In a receiver of the character described including an outer casing provided with an integrally and eccentrically formed cup member, and a magnet and cooperating parts secured within said cup member and said casing, a terminal block, binding posts secured in said terminal block and provided with means for securing said terminal block to said casing, a terminal for each of said binding posts, and means for securing each of said terminals on its binding post.

20. In a receiver of the character described including an outer casing provided with an integrally and eccentrically formed cup member, a permanent magnet and an electromagnet, and other cooperating parts secured within said cup member and casing, a terminal block secured to said casing, binding posts for said terminal block, said casing and terminal block being provided with openings for receiving terminals of a receiver cord to permit the connection of said terminals with said binding posts, said terminals having electrical connection with said electromagnet.

21. In a receiver of the character described including a casing provided with an integrally and eccentrically formed cup member, a permanent magnet and magnet coils secured within said cup member and casing, a terminal block secured to said casing, cylindrical members secured in said terminal blocks and electrically connected to said magnet coils, said terminal block and casing being provided with openings for receiving terminals of a receiver cord to permit the contactual engagement of said terminal and said cylindrical members, and means for engaging said cylindrical members and said terminals for retaining said terminals in contactual engagement with said cylindrical members.

22. In a receiver of the character described including a casing, a permanent magnet and magnet coils secured therein, a terminal block, binding posts secured in said terminal block by frictional engage-

ment, said binding posts adapted to secure said terminal block to said casing, said terminal block and easing adapted to receive the terminals of a receiver cord and to permit the terminals to engage said binding posts, screw members for engaging said binding posts to secure said terminals to said binding posts, and terminals for said binding posts to permit connection between said binding posts and said magnet coils. 10

Signed by me at Chicago, in the county of Cook and State of Illinois, this 1st day of March, 1921.

WILLIAM KAISLING.
